UNITED STATES PATENT OFFICE.

SILAS L. BOUND, OF CRAVENS, LOUISIANA.

DESIGN FOR A DRESSER, CHIFFONNIER, OR SIMILAR ARTICLE.

44,745.

Specification for Design.

Patented Oct. 21, 1913.

Application filed June 16, 1913. Serial No. 774,045. Term of patent 3½ years.

To all whom it may concern:

Be it known that I, SILAS L. BOUND, a citizen of the United States, residing at Cravens, in the parish of Vernon and State of Louisiana, have invented a new, original, and ornamental Design for Dressers, Chiffonniers, or Similar Articles, of which the following is a specification, reference being had to the accompanying drawings, forming part thereof.

In the drawings Figure 1 is a front elevation; Fig. 2 is a side elevation; and Fig. 3 is a top plan view.

What I claim is:

The ornamental design for a dresser, chiffonnier or similar article, as shown.

SILAS L. BOUND.
